CLAIM

The ornamental design for a housing for a vacuum cleaner, as shown and described.

DESCRIPTION

FIG. 1 is a front and right side perspective view of a housing for a vacuum cleaner showing our new design;

FIG. 2 is a left side elevational view thereof;

FIG. 3 is a top plan view thereof;

FIG. 4 is a bottom plan view thereof;

FIG. 5 is a rear elevational view thereof, of the first and second embodiment;

FIG. 6 is a front and right side perspective view of a second embodiment thereof;

FIG. 7 is a left side elevational view thereof;

FIG. 8 is a top plan view thereof; and

FIG. 9 is a bottom plan view thereof.

FIG. 1

FIG. 3

FIG. 4

FIG. 5

FIG. 2
